UNITED STATES PATENT OFFICE.

JOHN B. NEALE, OF BATTLE CREEK, MICHIGAN, ASSIGNOR OF ONE-HALF TO FRED W. GAGE, OF BATTLE CREEK, MICHIGAN.

OVERLAY.

1,178,870.

Specification of Letters Patent. Patented Apr. 11, 1916.

Application filed August 14, 1915. Serial No. 45,579.

To all whom it may concern:

Be it known that I, JOHN B. NEALE, a citizen of the United States, residing at Battle Creek, in the county of Calhoun and 5 State of Michigan, have invented certain new and useful Improvements in Overlays; and I hereby declare that the following is a full, clear, and exact description thereof, reference being had to the accompanying 10 drawings, which form part of this specification.

This invention or discovery relates to the art of printing, and has particular reference to the producing of fine high-grade illustrated work commonly called "half-tone" printing; and the object of the present invention is to provide a novel overlay by the employment of which such "half-tone" printing can be effected in a superior manner, and be successfully produced upon 15 grades of paper, such as uncoated book paper and ordinary newspaper stock, which have heretofore been considered impractical to use for such printing. Such novel overlays will also reduce the amount of labor, time 20 and skill required in "making ready" the press and enable superior half-tone printing to be produced on ordinary presses.

My invention is based upon the discovery 25 that by making overlays with a measurably yielding cushioned or resilient surface, as compared with the hard unyielding overlays heretofore employed, greatly superior results can be obtained in printing, such results being primarily due to the said resilient or cushion surface of the overlay.

The present invention consists in making 30 the overlays of resilient or cushioning material, such as rubber. Such an overlay can be produced in the following manner: An inked proof is taken from the original half-tone plate from which it is intended to print, and while fresh is given a coating of bronze, or other suitable finely divided opaque powder. This proof is then used as a negative 35 for printing upon the sensitized surface of a metal plate (properly prepared to take such print by the usual processes employed by metal etchers or engravers) making a reverse print of the same size as the original half-tone plate. This reverse print is then developed and rendered resistant to etching fluid by any suitable method. The printed plate is then etched to the depth desired in 40 the usual way, and may further be hand

tooled to make further changes in its tonal value if desired. The rubber overlay is then made from said etched plate in the usual way by pressure and heat, by any suitable means, sufficiently firm or hard to retain the 45 desired gradations and toning effects of an overlay, but retaining in itself sufficient resilience or yielding properties to give the desired cushioning effect. Such overlays made entirely of rubber, or other material, 50 which in itself possesses the necessary yielding or cushioning properties, when made of large size, have a tendency to shrink when vulcanized. Any shrinkage occurring in 55 small sized overlays of this kind could be overcome by stretching the overlay to position and fastening it down for printing purposes, but if the overlay is large, register may be insured by vulcanizing the overlay 60 upon a backing of wire netting of the kind 65 used for millers' bolting cloth, or a special fine and light netting could be used to hold the material of the overlay in register with the original plate from which it is desired 70 to print. In some cases a perforated flexible plate, or anything else that would prevent excessive shrinkage or contracting of the overlay when removed from the vulcanizing mold, or any suitable backing that will 75 not change its size nor be injuriously affected 80 by the processes of making the overlay in which it is employed, may be used.

In use such resilient cushioned overlay is placed upon the cylinder or platen of the press, just as an ordinary overlay would be placed. The superior results obtained in printing by using my invention are due to the yielding or cushioning nature of the overlay, rather than to any novelty in the mode of placing the overlay in the press, or 85 to any novelty in the mode of operating the press after the overlay is in position.

The ordinary overlays are usually "buried" 90 under a varying number of sheets of tympan paper, but I have found that this is not essential when using my invention; that is, were it not for the liability of mechanical injury my novel overlays might be placed on top of the tympan sheets and still be effective for some classes of work.

Upon some classes of printing it might be expedient to interpose more or less tympan paper between the overlay and the material to be printed, to obviate any tendency to over-effect. This is common practice with 110

any ordinary make-ready. A "patch" sheet or auxiliary overlay could be applied as usual to my overlay if desired to augment pressure at any particular point.

5 Pressmen will readily understand the many factors which enter into the production of a perfectly printed sheet and which may require minor changes of make-ready that do not alter the underlying principle of
10 the invention. My resilient or cushioned overlay is therefore subject to such variations of position and hardness as will produce the best results, as there is no fixed degree of resiliency or resistance that will
15 yield unvarying results upon all classes of printing.

With such novel overlays I am able to produce beautiful high-grade half-tone printing on ordinary newspaper stock, printing
20 the same in an ordinary flat bed or rotary press, and produce results which are equal or superior to those produced by the "Rotogravure" process. When printing on finer grades of paper the work produced is
25 superior in appearance to that produced by any of the heretofore known overlays or processes. The overlays may be also employed in printing upon fabrics and other material with greatly improved results, and
30 is also peculiarly adaptable to the production of loose-leaf catalogue illustrations in half-tone without resort to the off-set process of lithography now employed where fine illustrations must be shown upon bond or
35 ledger papers upon which it has hitherto been considered impossible to print successfully half-tone work.

In the accompanying drawing I have illustrated conventionally a magnified overlay
40 embodying my invention; said overlay as shown having a body 1, preferably formed of rubber or other suitable material, having a top or working surface, 2 which in itself possesses the necessary yielding or cushioning properties; and a backing or stiffening
45 3 of wire fabric or other suitable material; the said working surface may be formed with various projections as *a* and depressions as *b* according to the degree of variation
50 of pressure desired.

My novel overlays obviate the objectionable tendency of hard-surfaced overlays to crack, bend, or emboss the paper being printed. By using my novel overlays superior and hitherto unattainable effects can be produced from half-tone plates upon cheap

grades of newspaper, or rough-surfaced papers, upon which paper it has previously been impossible to produce impressions of the artistic character and quality produced
60 by the use of my invention, it having heretofore been an accepted maxim of the trade that highly surfaced paper is necessary for fine work in half-tone printing.

What I claim is:

1. An overlay formed of material providing in itself a resilient cushioning surface, for the purpose specified.

2. An overlay for use in half-tone printing composed of material having a limited
70 degree of resiliency or cushioning properties.

3. An overlay formed of material, having sufficient inherent elasticity to compensate for minute surface irregularities in the
75 paper or material being printed.

4. A self-contained overlay, formed integrally of rubber having a resilient cushioning surface, substantially as and for the
80 purpose set forth.

5. An overlay for use in half-tone printing, formed of rubber and having sufficient inherent elasticity to compensate for minute surface irregularities in the paper or material being printed.

6. An overlay formed of material providing a resilient cushioning surface, and a non-shrinkable backing, for the purpose
85 specified.

7. An overlay formed of material having sufficient inherent elasticity to compensate for minute surface irregularities in the
90 paper or material being printed, and a non-shrinkable backing.

8. A self-contained cushioned overlay, formed integrally of rubber providing a resilient cushioning surface, and a non-shrinkable backing, substantially as and for
95 the purpose set forth.

9. An overlay used for half-tone printing formed of material having sufficient inherent elasticity to compensate for minute surface irregularities in the paper or material being printed, and a backing of wire netting, substantially as described.

In testimony that I claim the foregoing as my own, I affix my signature in presence
100 of two witnesses.

JOHN B. NEALE.
